US00D631904S

(12) **United States Design Patent**
Kim et al.

(10) **Patent No.:** US D631,904 S
(45) **Date of Patent:** ** Feb. 1, 2011

(54) **PROJECTOR**

(75) Inventors: **Jae-Hyung Kim**, Gwangjoo-Si (KR);
Bo-Kyung Seong, Seoul (KR);
Jin-Wook Kim, Gimcheon-si (KR)

(73) Assignee: **Samsung Electronics Co., Ltd.** (KR)

(**) Term: **14 Years**

(21) Appl. No.: **29/359,764**

(22) Filed: **Apr. 15, 2010**

(30) **Foreign Application Priority Data**

Feb. 26, 2010 (KR) 30-2010-0008498

(51) **LOC (9) Cl.** **16-02**

(52) **U.S. Cl.** **D16/230; D16/225**

(58) **Field of Classification Search** D16/205,
D16/208, 221, 225, 230–231, 234; D21/514;
353/115, 119, 122

See application file for complete search history.
